UNITED STATES PATENT OFFICE.

GIACOMO MÉTTLER, OF BERLIN, GERMANY.

ELECTRIC FURNACE.

1,084,466.

Specification of Letters Patent. Patented Jan. 13, 1914.

Application filed November 28, 1911. Serial No. 682,953.

To all whom it may concern:

Be it known that I, GIACOMO MÉTTLER, a citizen of the Swiss Republic, residing at Berlin, in the Kingdom of Prussia and German Empire, have invented a new and useful Improved Electric Furnace, of which the following is a specification.

The invention relates to an electric resistance furnace which can be continuously charged and uniformly regulated up to temperatures of about 2400° C.

All parts of the furnace are easily accessible and exchangeable, and the contraction or warping of the parts cannot unfavorably influence the operation of the furnace.

In the drawings illustrating the invention by way of example: Figure 1 is a vertical section of the furnace, Fig. 2, a part section of another construction of the smelting shaft, Fig. 3, a plan of the plate over which the material to be melted falls into the smelting shaft, Fig. 4, a section through the insulating cone surrounding the electric resistance cone, showing a joint 61', and Fig. 5, a part section of another construction of the smelting shaft.

A circular iron mantle 1 (Fig. 1), which is provided with four or more hinges, about which it can be opened, surrounds a fire-proof mantle 2 of unslaked lime, which possesses a number of horizontal recesses or openings 3 to admit electric conductors. Inside this lining 2, and in the upper part of the furnace, are provided four or more supporting blocks 5, of fire proof material which have a segmental form in plan, and, underneath these blocks, there are four or more similar segmental blocks 6, which support segmental plates 6' of magnesia. The blocks 40 carry asbestos disks 7, on which the under surface 9, of the upper electric resistance carbon cone 8 bears, to the outer thickened end 10 of which the electric current is supplied by the copper poles 11. The thickness 45 of the cone 8 decreases toward its lower end, and this cone forms the shaft into which the material to be melted falls. The lower thin end 14 of this cone 8 fits into a carbon cone 15, which forms the smelting zone. 50 This cone 15 must therefore be able to expand without the contact between it and the upper cone 8 being disturbed and without one or the other of said cones being broken by unequal contraction. The lower cone 15 55 is provided with a horizontal extension 67, to which the other electric pole is connected,

and has further a vertical rib 18, which projects into the magnesia filling 19 which surrounds the upper carbon cone.

The furnace has two or more electric circuits (A—A and B—B), in which, for example, in the case of a furnace requiring a current of 50 H. P., the strength of the current can be transformed up to 1200 amperes, while the electromotive force of the alternating current is reduced to 25-10 volts.

All other hollow spaces in the furnace are preferably filled out with, or stamped full of, melted magnesia, which can be subsequently filled up as occasion requires. Immediately 70 underneath the smelting cone 15 there is a rectification chamber 20 consisting of, a cylinder 21 of highly burnt zirconium oxid, a top plate 22 preferably of the same material adjoining the smelting cone, and a bottom 75 plate 23 carried by the head 27 of a vertical cylindrical wall 24. The rectification chamber 20 is closed by a valve 26 made of zirconium oxid or other refractory material, which fits in a bottom opening in said chamber 80 and also bears against the head 27 serving as a valve seat. The valve 26 can be adjusted from below by means of a pipe 28 and rod 29 both of fireproof material. Said valve 26 can however also be pressed upward 85 by gases. If the pressure of the rod 29 and pipe 28, or of the gases, is reduced, the valve 26 will fall and the melted material can flow out. Through a channel consisting preferably of an inner pipe 30 and an outer pipe 31 90 made of fire proof material such as zirconium oxid or for lower temperatures chamotte, the contact surfaces of which are coated with graphite. The rectification chamber is also surrounded by an electric 95 resistance 8', made of carbon or other suitable material and having a tubular shape with a flange at top and bottom, switched into the circuit B—B.

The wall 21 of the refining chamber 20 is 100 only made of zirconium oxid when chemically pure silicates in small quantities are to be kept liquid in said chamber. At the back of the wall 21 a space is provided to permit contraction and expansion of said 105 wall and this space is filled with suitable metal carbids, such as carbid of tungsten or titanium. This space is necessary because the electric resistance 8' surrounding it need not expand and contract under the changes 110 of temperature in exactly the same degree as the wall 21. Said electric resistance heats

all the parts it incloses and is itself surrounded by any suitable heat-insulating material, such as magnesia, etc.

The furnace is charged by the worm 32 which is gastight. The air necessary for the preliminary heating enters through the hole 33, while the gases are drawn off through the openings 34. The worm 32 rotates in the casing 36, the top flange 37 of 10 which is provided with grooves 38 serving as a race for porcelain or steel balls 39. The horizontal disk 44 is integral with the worm 32 and is connected by screws 41 with the pulley 40 driven by the belt 43, asbestos disk 15 42 being interposed, in order to prevent the pulley 40 from becoming hot.

In operation the furnace is preliminarily heated by the burner 45, which is adapted to be raised and lowered in the pipe 46 and can 20 also be adapted to be rotated by being connected by the plate 46' with the pulley 40, as shown in dotted lines. The pipe 46 is extended into a disk 47 which repels the heat rising from the smelting shaft. The pipe 45 25 is provided with a shoulder which leaves a space 48 for the admission of water for cooling. At the top of this pipe, which is preferably made of porcelain containing chromium oxide (according to the process of Prof. 30 Marquardt) there is a rounded screwthread 49, so that a gas-tight metal pipe, or a joint-coupling, can be attached. By means of the pulley 40, or a spur-wheel, the worm 32 is 35 rotated, which takes up the material to be treated through the opening 50 and presses it down through the groove 52, whereupon it falls on the cone 8, which, toward its lower end, becomes more slanting facilitates the feed of the material toward the smelting 40 zone. Through the pipe 45 hydrogen, oxyhydrogen, or some other suitable, gas is supplied (which, according to the character of the material to be melted, must form an oxidizing or reducing flame 53), so that a vertical 45 downwardly directed flame is formed, which centrally heats the material. Because the point of the flame, or of several flames, communicates its temperature about 1700° C. to the quartz or metal to be melted, the material 50 soon becomes red hot, free from striæ, air, and constituent water etc., and becomes a better conductor. The electric current passes therefore into the smelting zone through the carbon shaft lining of zirconium 55 oxide or thorium oxide, without considerable resistance, and the melted material flows in the form of a thread or tube through the narrowest opening of the shaft. The current is conducted from the carbon cone to 60 the lining 54 and through this into the melted material, because the lining 54 which preferably consists of zirconium oxide fritted with sesquioxide of boron at the high temperature of the smelting zone becomes a good conductor of electricity. Between the re-

sistance cone and the lining may be provided a cement consisting of a mixture of sesquioxide of boron with zirconium oxide and silicate of potash and sulfid of ammonium. The ammonium sulfid renders the silicate of potash less viscous so that only quite small quantities are necessary for binding the sesquioxide of boron. Sesquioxide of boron and zirconium oxide are used in a finely pulverized condition. The cement made by melting together these substances is a good conductor of electricity and is very hard, remaining fire-proof at high temperatures. The carbon cone, at its narrowest point, also has the minimum thickness, and, accordingly, becomes hotter there than at any other point. At 2000° C. the lining 54 becomes a good conductor. It can also be fritted with sesquioxide of boron and some form of tungsten for instance tungsten oxide, in which case it 70 75 80 85 becomes a still better conductor.

No mold is necessarily used in connection with this furnace. In the case of silicates the valve 26 with which the lower end of the molten thread comes into contact and which normally closes the refining chamber, can be moved downward and when so moved slowly pulls the molten thread downward and in any case the refining chamber can only be used to collect a small quantity of 90 the molten material when silicates are being treated. The top of the valve pulls the molten thread at the same speed as it issues from the shaft. As soon as a certain length of the thread is reached the electric current can be caused to pass through said thread, the heated valve being a conductor of electricity at the high temperature in question. If the furnace is used for melting metals the tubes 30, 31 (as indicated by the 95 arrows) and the plate 23 and valve 26 can be removed so that the molten material can descend in the form of a thread into the mold or into any vessel arranged underneath the furnace in any suitable manner.

In the construction shown in Fig. 2 an inner cone 57 of zirconium bears against an intermediate layer 58 of tungsten, which can also be cemented with oxide of titanium or metallic titanium or made of suitable metal carbids (such as carbids of tungsten or titanium or other rare metals, for example yttrium) and serves to distribute the current better and to prevent undue heating at the narrowest point of the furnace and acts as an electric resistance. Outside the cone 57 there is an inner cone 57', of zirconium oxide or other suitable material which is backed by metal carbids 60, such as carbids of tungsten or titanium or other rare metals, for example 100 yttrium, which take up the current uniformly from the carbon cone 15. The inner coating of tungsten mentioned by way of example can also be cemented with sesquioxide of boron alone instead of titanium, a 105 110 115 120 125 130

mechanically tight connection with the zirconium cone being formed without the various coefficients of expansion being disturbed, and without the tungsten absorbing oxygen, or the distribution of the heat and the dilatation of the cone being prevented. This tungsten can be better protected from contact with carbonaceous gases by the zirconium cone 57 being fritted with sesquioxides of boron. The carbon cone is moreover insulated at the back by a cone 61 of zirconium oxid. This cone consists of several parts as shown in part sectional plan in Fig. 4 and is provided with strengthening ribs 62 which also serve to better support the carbon. The top plate 22 of the rectification chamber is beveled off and allows free play for the interior zirconium cone 57 (Fig. 2). The colder zone of the carbon cone is covered with a layer 63 (Figs. 1 and 2) of melted magnesia, which overlaps and bears against the zirconium cone 57. When using the furnace for finer metallurgical purposes the outer cones of the smelting zone must have larger dimensions and be formed as shown in Fig. 5.

In this furnace an inner cone of any suitable fireproof material covers a carbon resistance 8, the lower end of which is beveled off and is in contact with a similar surface of the carbon cone 15, which forms the heating zone proper. This bottom cone 15 is curved round at the bottom and ends in a horizontal flange 15'. This flange is covered with kryptol material which is a granular graphite and carbon mixture, universally used for making electric resistances. The back cone supporting the resistance cone has long ribs 62 so that this cone, as seen from the top, has a star shape. The space between the ribs is partially filled up with magnesia or the like, which falls in the direction of the arrows 19' and behind the plate 62' the kryptol material is provided. The plate 62' only serves to separate these two materials. The electric current is then caused to take the direction shown by the dotted arrows, being collected by the plate 81 and led off at 82. The inclined plate 80, preferably made in sections connected together by flanges 80'' and bolts 80', is designed to enable the magnesia 19 or the like to be inserted without becoming mixed with the kryptol material 66. The space between the concentric cones 57 and 57' may be filled with a layer consisting of metals or metal oxides of the chromium group, tungsten, titanium or their carbids alone or together.

In Fig. 1 C—C is a line along which the entire parts serving for the preliminary heating of the melting shaft can be mechanically lifted off. 68 designates insulating material such as quartz sand etc. The rectangular frame 69 supports, by means of the angle iron 70 the flange 37 and can be raised

or lowered with the assistance of the counter weight 72 suspended by a chain passing over the roller 71. This construction permits not only the casing 36 and all parts secured thereto, but also the burner 45, and the part 70 47, with ribs 47', to be raised. 34' are lids adapted to close the suction openings 34. 73 and 74 are insulating layers of magnesia. At the bottom of the furnace there is an iron plate 75 carried by rails 76 which can be 75 moved horizontally on beams 77.

I am aware that an electric furnace is known having a tapering heating chamber with walls containing carbon resistances faced with pyro-conductive material, delivering into a hearth having similar resistances in the sides, and that refractory materials having a comparatively high resistance at ordinary temperature but increasing in conductivity when heated may when applied to an electric furnace be heated by means of a blow-pipe or similar source of intense heat.

What I claim and desire to secure by Letters Patent of the United States is:—

1. An electric furnace, comprising in combination, an inverted gas burner, an electric resistance cone of carbon below said burner and made of several pieces fitting in each other, and a lining in said cone of a material 95 which conducts electricity at a high temperature, substantially as, and for the purpose, set forth.

2. An electric furnace, comprising in combination, an inverted gas burner, an electric 100 resistance cone of carbon below said burner and made of several pieces fitting in each other, a lining in said cone of a material which becomes a conductor of electricity at a high temperature, and a cone of fireproof 105 material outside said electric resistance cone made in several pieces and of fireproof material such as non-conducting zirconium oxid and having strengthening ribs, substantially as, and for the purpose, set forth.

3. An electric furnace, comprising in combination, an inverted gas burner, a carbon cone underneath said burner and consisting of several pieces fitting into each other the wall of which cone becomes more slanting 115 toward the middle, substantially as, and for the purpose, set forth.

4. An electric furnace, comprising in combination, an inverted gas burner, a pipe enclosing said burner and extending into a disk having heat distributing ribs, an electric resistance cone of carbon below said burner and made of several pieces fitting in each other, and a lining in said cone of a material which becomes a conductor of electricity at a high temperature, substantially as, and for the purpose, set forth.

5. An electric furnace, comprising in combination, an inverted gas burner, a pipe enclosing said burner and leaving a space be- 130

- 5   between said burner and pipe for water cooling, an electric resistance cone of carbon below said burner and made of several pieces fitting in each other, and a lining in said cone of a material which becomes a conductor of electricity at a high temperature, substantially as, and for the purpose, set forth.
- 10   6. An electric furnace, comprising in combination, an inverted gas burner, a pipe enclosing said burner, a worm surrounding said pipe, a casing surrounding said worm, an electric resistance cone of carbon below said burner and made of several pieces fitting in each other, and a lining in said cone of a material which becomes a conductor of electricity at a high temperature, substantially as, and for the purpose, set forth.
- 15   7. An electric furnace, comprising in combination, an inverted gas burner, an electric resistance cone of carbon below said burner and made of several pieces fitting in each other, a lining in said cone of a material which becomes a conductor of electricity at a high temperature, and a rectifying chamber underneath said cone the top plate of which chamber has a rounded nozzle form adjoining the lining of the cone, substantially as, and for the purpose, set forth.
- 20   8. An electric furnace, comprising in combination, an inverted gas burner, an electric resistance cone of carbon below said burner and made of several pieces fitting in each other, a lining in said cone of a material which becomes a conductor of electricity at a high temperature, a rectifying chamber underneath said cone, a cone closing the bottom end of said chamber, and means to operate said closing cone, substantially as, and for the purpose, set forth.
- 25   9. An electric furnace, comprising in combination, an inverted gas burner, an electric resistance cone of carbon below said burner and made of several pieces fitting in each other and having an extension projecting into granular carbon, and a lining in said cone of a material which becomes a conductor of electricity at a high temperature, substantially as, and for the purpose, set forth.
- 30   10. An electric furnace, comprising in combination, an inverted gas burner, an electric resistance cone of carbon below said burner and made of several pieces fitting in each other, a lining in said cone of a material which becomes a conductor of electricity at a high temperature, a cone of fireproof material outside said electric resistance cone made in several pieces and of fireproof material such as non-conducting zirconium oxid and having strengthening ribs, a granular electric insulating filling of magnesia between the electric resistance cone and the insulating cone, and a cone supporting said filling, substantially as, and for the purpose, set forth.
- 35   11. An electric furnace, comprising in combination, an inverted gas burner, an electric resistance cone of carbon below said burner and made of several pieces fitting in each other, a lining in said cone of a material which becomes a conductor of electricity at a high temperature, and a cement between the abutting surfaces of the electric resistance cone and lining consisting of a mixture of sesqui-oxid of boron silicate of potassium and sulfid of ammonium, substantially as, and for the purpose, set forth.
- 40   12. An electric furnace, comprising in combination, an inverted gas burner, an electric resistance cone of carbon below said burner and made of several pieces fitting in each other, a lining consisting of two concentric cones leaving a space between them, and a layer consisting of metals or metal oxides of the chromium group, tungsten, titanium, or their carbids, or of other fireproof metals, which may be fritted with sesquioxid of boron in said space, substantially as, and for the purpose, set forth.
- 45   13. An electric furnace, in which all parts subject to stresses are fritted with sesqui-oxid of boron, substantially as, and for the purpose, set forth.
- 50   14. An electric furnace, comprising in combination, a revoluble gas burner, an electric resistance cone of carbon below said burner and made of several pieces fitting in each other, and a lining in said cone of a material which conducts electricity at a high temperature, substantially as, and for the purpose, set forth.
- 55   In testimony whereof I have signed my name to this specification in the presence of two subscribing witnesses.
- 60   GIACOMO MÉTTLER.
- 65   Witnesses:
- 66   HENRY HASPER,
67   WOLDEMAR HAUPT.
